EXPANSIBLE LINK CHAIN FOR A BRACELET
OR THE LIKEJoseph M. Bender, Manhasset, N. Y., assignor to
Jacoby-Bender, Inc., New York, N. Y., a corpo-
ration of New York

Application November 30, 1948, Serial No. 149,881

Term of patent 7 years

(Cl. D45—4)

To all whom it may concern:

Be it known that I, Joseph M. Bender, a citizen of the United States and a resident of Manhasset, county of Nassau, and State of New York, have invented a new, original, and ornamental Design for an Expansible Link Chain for a Bracelet or the like, of which the following is a specification, reference being had to the accompanying drawing, forming a part thereof, in which:

Fig. 1 is a top view of the chain showing my new design in contracted condition;

Fig. 2 is a top view thereof in partially expanded condition with the conventional bottom links visible between the expanded top links.

Fig. 3 is a top view of one of the individual top links of the chain;

Fig. 4 is a side elevational view of the link of Fig. 3; and

Fig. 5 is an end elevational view of the link of Fig. 3.

I claim:

The ornamental design for an expansible link chain for a bracelet or the like, as shown and described.

JOSEPH M. BENDER.
